Lacy Haug, Mysa

UNITED STATES PATENT OFFICE.

HERMAN REINL, OF SECAUCUS, NEW JERSEY.

SASH-LOCK.

1,339,670.

Specification of Letters Patent. Patented May 11, 1920.

Application filed October 15, 1919. Serial No. 330,772.

To all whom it may concern:

Be it known that I, HERMAN REINL, citizen of the United States, residing at Secaucus, in the county of Hudson and State of New Jersey, have invented certain new and useful Improvements in Sash-Locks, of which the following is a specification.

This invention relates to improvements in locks especially adapted for use on windows.

An important object of this invention is to provide a sash lock having novel means whereby the lock may be retained in inoperative position during various adjustments of the window.

A further object of this invention is to provide a window lock of the sliding bolt type and having a novel form of spring actuated catch for retaining the bolt in inoperative position, said spring actuated catch being provided with a manipulating means arranged within convenient reach whereby the window may be readily locked after the same has been closed.

A further object of the invention is to provide a lock of the class described which may be readily and conveniently applied to a window and which when applied will present an extremely neat appearance.

A further object of the invention is to provide a lock of the class described which is of highly simplified construction, cheap to manufacture, and desirable in use.

Other objects and advantages of the invention will be apparent during the course of the following description.

In the accompanying drawing forming a part of this application and in which like numerals are employed to designate like parts throughout the same:

Figure 1 is a perspective view of the improved lock applied,

Fig. 2 is a central vertical longitudinal section through the same,

Fig. 3 is a vertical transverse section taken on line 3—3 of Fig. 2, and

Fig. 4 is a fragmentary section through the lock casing or housing and illustrating a slightly modified form of catch operating spring.

In the drawing, wherein for the purpose of illustration is shown a preferred embodiment of the invention, the numerals 5 and 6 designate upper and lower sash which, as usual, are adapted for vertical movement.

As illustrated in Fig. 1, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

As illustrated in Fig. 2, the improved lock includes a rectangular casing or housing 7 having its sides 8 extended and bent outwardly to form attaching flanges 9. The attaching flanges 9 may be secured to the upper side of the sash 6 by screws 10 or other suitable fastening devices.

by a latch plate or arm 24 whereby the bolt may be retained in a retracted position. The laterally projecting trigger or arm 24' is provided with a reduced head 25 which is 5 adapted to be received within an opening or locking recess 26 when the bolt is in its rearward or retracted position. The reduced head 25 forms a pair of shoulders 25' which serve to limit the downward pivotal movement 10 of the latch. The locking plate or latch 24 is pivotally connected at its forward end portion to an anchoring member 27 through the medium of interfitting hinge barrels 28. A coil spring 29 is arranged 15 between the latch 24 and the anchoring plate 27 and has its terminal arms 30 anchored to the plates 24 and 27 by solder or other means. When the bolt 14 is moved rearwardly by a corresponding movement of 20 the knob 20, the head 25 of the trigger is received within the recess 26 and the bolt is, therefore, held in a retracted position by the latch 24. The tension of the coil spring efficiently retains the latch 24 in engagement 25 with the trigger 24'.

As illustrated in Figs. 1 and 2, the rear end portion of the catch 24 is extended rearwardly through an opening 31 in the rear side of the housing and is adapted to be 30 manually elevated for releasing the head 25 from the opening or locking recess 26. Instantaneously upon the release of the trigger 24', the bolt is moved forwardly by the coil spring 19 and is received within the 35 opening 15.

In the modified form of invention illustrated in Fig. 4, the latch 24 is provided with a longitudinal groove 32 which slidably receives one terminal arm 30 of the coil spring 29. The groove 32 securely retains the terminal arms of the coil spring in position and eliminates any binding of the spring as a result of the pivotal movement 40 of the plate with relation to the coil spring.

In the practice of the invention the casing 45 and keeper 16 are applied to the adjacent ends of the window sections as illustrated in Fig. 1. When it is desired to leave the window unlocked or open, the bolt 14 is drawn rearwardly by a corresponding movement 50 of the knob 20 and is held in its retracted position by the latch 24. When the lower sash 6 has been lowered and it is desired to lock the window, the rear end portion 55 of the latch 24 is elevated whereby the reduced head 25 is released from the locking recess 26. The bolt is then moved forwardly into the opening 15 whereby the upper and lower sections of the window are 60 securely locked against movement. When it is desired to again open the window, the knob 20 is drawn rearwardly by a manual movement for releasing the bolt 14 from the keeper.

As illustrated in Fig. 2, the barrel 11 is

provided with a longitudinally extending slot 33 which permits the free movement of the trigger 24' with the bolt 14.

It is to be understood that the form of the invention herewith shown and described is to 70 be taken as a preferred example of the same and that such minor changes in arrangement and construction of parts may be made as will remain within the spirit of the invention and the scope of what is claimed. 75

Having thus described the invention, what is claimed as new is:

1. A lock of the class described including a casing, a barrel arranged within the casing and secured to the opposite ends of the 80 same, a bolt slidably carried by said barrel and having a laterally projecting trigger, a latch horizontally pivoted at its forward end within said casing and having a recess intermediate of its ends adapted for the reception of said trigger, spring means associated with said latch for positively connecting the same with said trigger, the rear end portion of said latch being disposed exteriorly of said casing, and a keeper associated with 85 said bolt, said latch being inclined downwardly from its pivoted end to its free end whereby said trigger in moving rearwardly in a horizontal plane will be directed into the trigger receiving recess within the latch. 95

2. A lock of the class described including a rectangular casing, a sliding bolt carried by said casing, a laterally projecting trigger carried by said bolt and having a reduced upwardly extending head, a latch horizontally pivoted at its forward end within said casing and having an opening receiving the reduced head of said trigger, spring means to positively engage said latch with said trigger, the rear end portion of said latch being extended through said casing whereby the same may be moved vertically for releasing said trigger, and spring means for urging said bolt forwardly. 100

3. A lock of the class described including a casing, a bolt slidably carried by said casing, a laterally projecting trigger connected to said bolt and having its upper portion provided with a reduced head thereby forming a pair of shoulders, a latch horizontally pivoted at its forward end within the forward portion of said casing and having a recess intermediate its ends to receive the reduced head of said trigger, the shoulders on said trigger being adapted to limit the downward movement of said latch, a spring associated with said latch for urging the same downwardly into engagement with said trigger, and a keeper associated with 110 said bolt. 115

4. A lock of the class described including a casing, a barrel extending longitudinally of the casing, a bolt slidably carried by said barrel, a trigger connected to said bolt, a latch horizontally pivoted at its forward 120 125 130

end within said casing and adapted to be engaged by said trigger, said latch being provided with trigger engaging means, spring means associated with said latch for securely connecting the same to said trigger, spring means urging said bolt forwardly, and a keeper associated with said

bolt, said latch being inclined downwardly toward its rear end whereby said trigger in moving rearwardly in a horizontal plane 10 will be directed into the trigger engaging means of said latch.

In testimony whereof I affix my signature.

HERMAN REINL. [L.S.]
